United States Patent Office.

HOSEA BARNES, OF SOMERS, WISCONSIN.

Letters Patent No. 72,444, dated December 24, 1867.

IMPROVEMENT IN EXTENSION-LADDER.

The Schedule referred to in these Letters Patent and making part of the same.

TO ALL WHOM IT MAY CONCERN:

Be it known that I, HOSEA BARNES, of Somers, in the county of Kenosha, and State of Wisconsin, have invented a new and improved Extension-Ladder; and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention consists in connecting together several sections or lengths of ladder, (three, more or less,) in such a manner that the sections may be rigidly connected so as to form one continuous length when required, and admit of the lengths being folded when not required for use, and also adjusted so as to form a step-ladder when required. In the accompanying sheet of drawings—

Figure 1 is an elevation of my invention extended at full length for use.

Figure 2, a side sectional view of the same, taken in the line *x x*, fig. 1.

Similar letters of reference indicate like parts.

A B C represent the three sections or lengths of the ladder, A being the lowest or first section, B the second, and C the third or uppermost section. The lower ends of the side pieces *a a* of the sections B and C are notched, as shown at *b b* in fig. 2, and these sections are connected together by having the rounds *c* of the sections A and B pass through oblong slots *d* in the lower parts of the side pieces of B and C, said slots admitting of the notches *b* being fitted on the rounds *c* below *c*, as shown in fig. 2. The parts B C have hooks D attached to their side pieces *a*, one or both of them, and at such points as to admit of the hooks being adjusted over the rounds *c c*. These hooks, when thus adjusted, prevent the sections B C being raised, and the notches *b b* therefore cannot pass off and be free from the rounds *c*, and the sections A B C will consequently be rigidly connected together and form a continuous ladder equally as strong and firm as one made in a single length or piece. By detaching the hooks D from the rounds *c*, the sections or lengths may be folded over and adjusted in the form of a triangle to constitute a step-ladder.

I do not claim broadly a folding ladder, or one made in sections connected by joints, for they have been previously used; but

I do claim as new, and desire to secure by Letters Patent—

The hooks D, attached to the side pieces *a* of the sections or lengths B C, when the latter are connected together by the rounds *c* passing through oblong slots *d* in the side pieces *a*, and the lower ends of the latter are provided with notches *b*, to fit over rounds *c*, all arranged in the manner substantially as shown and described.

HOSEA BARNES.
